UNITED STATES PATENT OFFICE.

THOMAS H. EULASS, OF LEBANON, OHIO.

DEVICE FOR HOLDING STRAPS OR ROPES.

SPECIFICATION forming part of Letters Patent No. 246,105, dated August 23, 1881.

Application filed June 20, 1881. (Model.)

To all whom it may concern:

Be it known that I, THOMAS H. EULASS, of Lebanon, Warren county, Ohio, have invented a new and useful Improvement in Devices for Holding Straps and Ropes, such as halter-straps, clothes-lines, &c.; and I do hereby declare the following to be a full, clear, and exact description of the same, reference being had to the annexed drawings, making a part 10 of this specification.

My invention relates to a device for holding straps and ropes, as hereinafter described.

Figure 1 is a perspective view of my invention as constructed for use on a hitching-rack. Fig. 2 is a view of the swinging latch detached.

I use a latch, A, made of iron, steel, brass, or other suitable material. The bottom of said latch, which comes in contact with the strap or rope, is corrugated, as shown. The top of said latch, which comes in contact with the staple B, is grooved, as shown. The upper corners or ends of the latch A project at right angles with the body, as shown in Fig. 2.

25 In the groove of the latch, and between the

projecting corners or ends, I place a staple, B, Fig. 1, which is driven in or otherwise secured to the rack-post or other place upon which the device is desired to be used for the purpose of holding the latch to its place. Just back of 30 staple B, I secure another staple, C, Fig. 1, for the purpose of preventing the latch from being displaced or thrown forward by an upward jerk of the strap or rope.

To operate my invention, pass the strap or 35 rope through the staple C and under the staple B, and then beneath the latch A, when on pulling the reverse way the strap will be found to be fast beneath the latch.

What I claim as my invention, and desire 40 to secure by Letters Patent, is—

An improved rope or strap holder, consisting of the staples C and B and corrugated latch A, all arranged substantially as shown, and for the purpose set forth.

THOMAS H. EULASS.
